UNITED STATES PATENT OFFICE

2,531,591

TOY PISTOL

Elijah J. Willis, Morehead City, N. C., assignor
of one-half to Alfred B. Cooper, Morehead City,
N. C.

Application May 29, 1946, Serial No. 673,903

2 Claims. (Cl. 124—27)

1

This invention relates to a game of skill, and the primary object of the invention is to provide a game device for use with a target having electrical contacts incorporated therein which are adapted to be closed by the prong of a dart propelled at the target by the device.

Another object of the invention is to provide a game device that is attractive, adapted for playing the game indoors or outdoors and which will afford the users thereof considerable enjoyment and entertainment.

With the above and other objects and advantages in view, the invention consists of the novel details of construction, arrangement and combination of parts more fully hereinafter described, claimed and illustrated in the accompanying drawings in which:

Figure 1 is an elevational view of the game device.

Figure 2 shows a glider in use with the game device.

Figure 3 is the same as Figure 1 with the side removed.

Figure 4 is a front view.

Figure 5 is a sectional view on the line 5—5 of Figure 1, and

Figure 6 is a top plan view.

Referring more in detail to the drawings, the game device comprises a projector 106 which may be used to propel darts 108, Figure 3, or a glider 160, Figure 2.

The darts are propelled at a target, not shown, by means of the projector 106 shown in Figure 1 which comprises the substantially triangular shaped body 108 having the removable cover 110, having grip 112 and pivoted sight 114.

Mounted for pivotal movement with the body 108 by means of the pin 116 is the projector arm 118 which is provided with an elongated slot 120 for the pivoting thereof, so that in its forward movement under impulse of the spring 122 secured thereto and to the body the guide pin 124 will slide in the guide slot 126, and the arm will not extend upwardly from its normal position in relation to the body at the top thereof but move forward in a substantially straight line to propel the dart. A second spring 128 secured to the bottom of the arm also adds impetus to the arm and dart.

The arm is provided with a pin 130 which is adapted to be engaged by the hooked end 132 of the keeper 134 pivoted at 136. A spring 138 retains the keeper 134 in engagement with the pin 130 until it is moved out of engagement therewith by means of the cable 140 secured thereto

and actuated by the trigger 142 pivoted at 144 in the body 108. The cable 140 is trained through the guide eye 146 to prevent the cable from becoming entangled in the spring 128, and a trigger guard 148 is provided for the trigger 142. The barrel 150 of the body is provided with a longitudinal bore 152, having opposed parallel slots 154 which are parallel with the guideway 126 and the dart is positioned in the bore and slots for the propulsion thereof as shown in dotted lines in Figures 3 and 4.

A hand grip 156 is provided adjacent the trigger guard 148 for the handling of the body and the arm 118 upon reaching its extended position contacts the rubber bumper 158.

The projector 106 may also be used to propel a glider 160 and the glider is positioned for the propulsion thereof as shown in Figure 2.

Thus a game device has been provided that will afford amusement for young and old alike, and may be used for projecting a dart during the course of playing a game or may also be used as a projector for a glider for further enjoyment thereof.

It is believed that the structure of the component parts thereof will be apparent to those skilled in the art, and it is to be understood that changes in the minor details of construction of the various parts may be resorted to provided they fall within the spirit of the invention, and the scope of the appended claims.

Having thus described the invention, what is claimed as new and desired to be secured by Letters Patent is:

1. A game device of the character described comprising a substantially triangular shaped body, a barrel portion on the upper or largest edge of said body, a hand grip on said body for holding said body in projecting position, a projector arm pivoted in said body, a spring secured to said body and said arm for lending impetus thereto, a spring pressed latch engaging said arm to retain it in cocked position, the movement of said latch to disengage said arm permitting said spring to impel said arm forwardly from its cocked position to impel a projectile at an object, guide slots in said barrel longitudinally thereof, a guide pin in said arm receivable in said slots, and said arm being provided with an elongated slot at the lower end thereof through which the pivot pin for the arm extends so that the projectile engaging portion of the arm is adapted to move in a straight trajectory in its forward movement under impetus of the spring.
2. A game device of the character described

comprising a body, a barrel portion on the upper edge of said body, means on said body for holding said body in projecting position, a projector arm pivoted in said body, a spring secured to said body and said arm for lending impetus thereto and a spring pressed latch engaging said arm to retain it in cocked position, the movement of said latch to disengage said arm permitting said spring to impel said arm forwardly from its cocked position to impel a projectile at an object, guide slots in said barrel, a guide pin in said arm receivable in said slots, said arm being provided with an elongated slot through which the pivot pin for the arm extends so that the projectile engaging portion of the arm is adapted to move in a straight trajectory in its forward movement under impetus of said spring.
